UNITED STATES PATENT OFFICE.

FREDERICK R. ROBERTS, OF CONCORD, NEW HAMPSHIRE, ASSIGNOR TO WILLIAM B. DURGIN CO., OF CONCORD, NEW HAMPSHIRE, A CORPORATION OF NEW HAMPSHIRE.

DESIGN FOR A SPOON OR SIMILAR ARTICLE OF MANUFACTURE.

Application filed November 18, 1921. Serial No. 516,208. Term of patent 14 years.

To all whom it may concern:

Be it known that I, FREDERICK R. ROBERTS, a citizen of the United States of America, residing at Concord, in the county of Merrimack and State of New Hampshire, have invented a new, original, and ornamental Design for a Spoon or Similar Article of Manufacture, of which the following is a specification, reference being had to the

accompanying drawing, forming a part thereof.

In the drawings,

Figure 1 is a front view of the design.

Figure 2 is a rear view.

I claim:

The design for a spoon or similar article of manufacture as shown.

FREDERICK R. ROBERTS.
